(57) **CLAIM**

We claim an ornamental design for a sheath over catheter, as shown.

DESCRIPTION

FIG. 1 is a perspective view of a sheath over catheter of the present design;

FIG. 2 is an enlarged end elevation view thereof;

FIG. 3 is an enlarged opposite end elevation view thereof;

FIG. 4 is a top plan view thereof;

FIG. 5 is a bottom plan view thereof; and,

FIG. 6 is a side elevation view thereof, the opposite side view being a mirror image thereof.

The features shown in broken lines depict environmental structure only and form no part of the claimed design.
